WIRE TIGHTENER

George W. Clark, Timber Lake, S. Dak., assignor
of one-fourth to Julian O. Rostvedt, Bismarck,
N. Dak.

Application October 19, 1937, Serial No. 169,883

2 Claims. (Cl. 254—77)

This invention relates to an improved wire tightener.

It is well known that, in building and setting up the wood forms used in concrete construction work, it is necessary that the forms be retained in exact vertical or plumb position.

One of the principal objects of my invention is, therefore, to provide a wire tightener which will permit the ready tightening or loosening of the wire loops employed for binding together elements of the wood forms so that said elements of said forms will be effectively retained in proper vertically aligned position during the pouring of the concrete and while the concrete is hardening in the forms.

Another object of the invention is to provide a wire tightener which may be mounted on the wood forms in such a manner that accidental disengagement of the tightener will be prevented.

20 A further object of the invention is to provide a device of this character which will employ a tightening screw, which screw is formed with a swivel cap which will prevent embedding of the screw in the wood of a form during a wire tightening operation.

25 As a further object, the invention seeks to provide an improved wire tightener which will be characterized by the utmost simplicity and which may be cheaply manufactured and placed in use with the greatest facility.

30 Other and incidental objects of the invention not hereinabove mentioned will become apparent during the course of the following description.

35 My invention is illustrated in the accompanying drawing wherein:

Figure 1 is a side elevation showing my device as it would appear in operative position on a rail of a wood form, the view being partly broken away and shown in section.

40 Figure 2 is a longitudinal sectional view on the line 2—2 of Figure 1, looking in the direction indicated by the arrows.

45 Referring now more particularly to the drawing, wherein like numerals of reference will be seen to designate like parts throughout the views, the numeral 1 indicates, in general, a portion of a wood form such as is commonly employed for forming concrete walls and the like. The numeral 2 indicates a strand of binding wire which is employed for binding portions of the form together.

50 In carrying my invention into effect, I employ a body 3 which is, as best seen in Figure 2, of oblong shape and is tapered toward one end. The body is formed of cast metal or other suit-

able material and is provided with a rounded end 4. At its opposite end, the body is turned downwardly to provide a right angularly disposed leg 5. Formed in the body medially of its width and near the end thereof carrying the leg 5, is an opening 6 through which is adapted to extend a nail 7, or other fastening device. Although the nail or other fastening device may be dispensed with, if desired, it has been found that such a fastening device tends to prevent slipping of the body in a lateral direction. Formed in the side edges of the body medially of its length are oppositely disposed curved notches 8 and 9 which are, in use, adapted removably to receive portions of the binding wire 2.

55 It will be seen that by virtue of the fact that I have employed the leg 5, the body 3 will be adapted to be positioned in parallel relation to the top rail of the form with which the device is being used.

20 In order to effect a wire tightening operation, I employ a tightening screw 10 which is best seen in Figure 1 of the drawing. The tightening screw includes a threaded shank 11 which has a reduced head at its lower end, which head is shown in dotted lines at 12. The head is adapted to receive a cap 13 adapted to be swivelly mounted. At its upper end the tightening screw is provided with a handle 14. The threaded shank 11 is adapted to be screwed through the end of the body opposite that from the leg 5 and, as will be seen, when the cap 13 is engaged with the upper edge of a portion of a wood form and the leg 5 is engaged with the same surface, rotation of the handle 14 will cause the body 3 to rock upwardly and downwardly toward and away from the upper surface of the form.

30 Although it is believed that the operation of the device will be apparent from the foregoing description, a brief statement relative thereto here follows:

35 After the device has been mounted on the upper rail of a wood form and the nail 7, if desired, has been placed through the opening 6 and sunk into the rail, the strand of wire 2 is looped about the rails of the form and is extended upwardly to project over the upper surface of the body 3. Portions of the wire will lie in the grooves 8 and 9 and will, therefore, be prevented from slipping lengthwise of the body. As the grooves are 40 rounded, cutting of the wire by sharp edges will be prevented. The free ends of the strand of wire are then twisted together, as shown at 15, it being understood that the tightening screw will be rotated counterclockwise so that the end of 45

the body carrying the screw will lie as close to the rail of the wood form as possible. After the wire has been twisted and it is desired to further tighten the wire about the form, it is only necessary to rotate the handle in a clockwise direction which will cause the end of the body carrying the screw to raise and will, therefore, cause tightening of the strand of wire about the form. It will be seen, therefore, that after the rails of the wood form have been located in a desired position, they may be effectively bound in this position by the use of my improved device. When it is desired to loosen the wire loop, it is only necessary to rotate the tightening screw in a counterclockwise direction.

My improved wire tightening device is characterized by the utmost simplicity and efficiency. It may be used wherever the need for such a device arises and it should, therefore, be under-

stood, that I do not limit myself particularly to the purpose set forth.

Having thus described the invention, what I claim is:

1. As a new article of manufacture, a wire 5 tightener including a body having a leg engageable with one of the rails of a form, and a tightening screw carried by the body at the opposite end thereof from the leg and also engageable with said rail, said screw being rotatable for 10 swinging the body upwardly, with the leg as a pivot, and tightening a loop surrounding the rails and the body, about said rails.

2. As a new article of manufacture, a wire tightener including an elongated body having an 15 integral depending rigid fulcrum at one end, and a screw at the other end rotatable for swinging the body upwardly about the fulcrum for tightening a loop through which the body passes.

GEORGE W. CLARK. 20
